UNITED STATES PATENT OFFICE

136,319

DESIGN FOR A CASE FOR CIGARETTES OR THE LIKE

Fred M. New, New York, N. Y.

Application April 17, 1943, Serial No. 109,991

Term of patent 3½ years

To all whom it may concern:

Be it known that I, Fred M. New, a citizen of no country (having applied for final United States citizenship papers) and residing at New York, county and State of New York, have invented a new, original, and ornamental Design for a Case for Cigarettes or the like, of which the following is a specification, reference being made to the accompanying drawing, forming a part thereof.

Fig. 1 is a front perspective view of a case for cigarettes or the like in closed position and showing my new design.

Fig. 2 is a side elevational view of the case in open position.

Fig. 3 is a right hand perspective view of Fig. 2.

Fig. 4 is a perspective view of the case with its cover in retracted position.

The characteristic features of my design reside in the case of the configuration shown having a rectangular holding case and a cover of triangular shape hinged along the lower edge of one of the end walls of said holding case, the side panels of said cover overlapping the side walls of the holding case and extending diagonally from one corner to another corner of said holding case.

I claim:

The ornamental design for a case for cigarettes or the like, substantially as shown and described.

FRED M. NEW.
